UNITED STATES PATENT OFFICE.

JEROME L. BOYER, OF READING, PENNSYLVANIA.

APPARATUS FOR LOADING PIG-IRON.

SPECIFICATION forming part of Letters Patent No. 423,548, dated March 18, 1890.

Application filed May 20, 1889. Serial No. 311,437. (No model.)

To all whom it may concern:

Be it known that I, JEROME L. BOYER, a citizen of the United States, residing at Reading, in the county of Berks and State of Pennsylvania, have invented certain new and useful Improvements in Apparatus for Loading Pig-Iron; and I do declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to an apparatus intended more particularly for lifting pig-iron from the beds and carrying and depositing the same.

In the ordinary method of handling pig-iron in a blast-furnace the pigs are broken from the sows while they are still very hot, and after waiting until they are sufficiently cool to permit it each individual pig is picked from the bed by a laborer and carried to a 25 truck running lengthwise through the center of the cast-house.

In order to provide for the greatest possible yield from the furnace, it is advantageous to remove the pigs promptly, and the unavoidable severity of the labor is greatly increased, especially in warm weather, by the great heat arising from the pigs.

30 My object is to provide an improved apparatus which will do away with this hard and expensive labor, and at the same time avoid the necessity of waiting until the pigs are sufficiently cooled; and my invention is fully set forth herein and specified in the claims.

Figure 1 represents my complete apparatus 40 as applied to the cast-house of a blast-furnace. Fig. 2 is a separate view of my improved grappling device.

Upon overhead tracks B, parallel with the side walls of the cast-house, runs a carriage C, which spans the whole width of the house, and which carries a trolley D. Flexibly suspended by the yoke d and joint t from this trolley is a cylinder E, within which works a piston e, whose rod f, passing through the cylinder-head v, is connected by a swivel-joint g to a rod F; which carries the grappling device. The latter consists of claws G, shaped

to adapt them to the special work for which they are designed, and pivoted at points w to a cross-bar H, which slides upon the lower end of the bar F above the head k on the latter. The upwardly and outwardly extended shanks l of the claws G are pivoted to one end of toggle-bars L, the other ends of which are pivoted at points h to the bar F. A flexible cord M has two branches, which pass over pulleys n, secured to the rod F above the toggle-bars L, and are connected to the ends of the extended shanks l of the claws G.

R represents a steam-tight tank or reservoir which contains water or a non-congealable liquid, such as a mixture of glycerine and water, or other suitable medium for transmitting power to the cylinder E. This medium may fill the reservoir to the height of the dotted line x, to the space above which steam may be admitted through an inlet-pipe r, regulated by a suitable valve, and from which the same may be exhausted through a similar pipe s. A flexible tubing S connects the reservoir 75 with the lower end of the cylinder E.

N represents a narrow-gage track ordinarily running lengthwise through the center of the cast-house. A truck P, provided with bars p, which form a frame to support the pigs q, is 80 moved upon the track.

The operation of my apparatus is as follows: The carriage C may be moved by any suitable means to a position above or approximately above each successive row of pigs, and the 85 trolley D may be moved sidewise, as desired. The grappling device being suspended above a row of pigs lying in the pig-bed, the claws G may be opened by pulling on the cord M, and upon closing the inlet-pipe r and opening 90 the exhaust-pipe s into the reservoir R the piston e is lowered by gravity until the claws enter the sand of the pig-bed, as indicated in Fig. 1. Now upon closing the discharge and opening the inlet the medium is forced into 95 the cylinder E, raising the piston e and the rod F. The movement of the latter by means of the toggle-connection described first closes the claws G to the position indicated in Fig. 2, thus inclosing as many pigs as were spanned 100 by the claws when opened. When the head k on the lower end of rod F comes in contact with the cross-bar H, the continued raising of said rod elevates the claws, together with the

inclosed pigs, the lifting-strain coming upon the pins *w*, while the toggle-bars *L* maintain the claws in their closed position. Having been raised to a proper height, the trolley *D* and its suspended load are moved over the truck *P*, the grappling device is turned on the swivel *g* and lowered, as before explained, until the pigs *q* rest upon the truck-bars *p*, when the claws are opened again by pulling upon the cord *M* and returned to the pig-bed for another load.

I am aware that a suspended grappling device has been heretofore operated by means of power transmitted thereto through a flexible conduit, and also that grappling devices have been so constructed that the claws are closed by the first raising of the rod and the load itself lifted by the continued raising. In my device, however, the claws are not closed against the load or against each other, but the points are always free from compression, and are consequently but little worn. They are prevented from spreading when sustaining a load by the toggles *L*, but may be readily opened when light by pulling upon the cord *M*. The toggles are above the pivotal points of the claws, and do not therefore interfere at all with the load.

I do not limit my invention to the exact

construction and arrangement herein particularly set forth or for the special purpose described; but

What I claim is—

1. In a loading apparatus, the combination, with a suspended rod having an enlarged lower end, of a grappling device consisting of claws pivoted to a cross-bar sliding on said rod, and toggle-bars having one end pivoted to the extended ends of said claws above said cross-bar and the other end pivoted to said rod, all arranged and adapted to operate substantially as set forth. 35

2. In a loading apparatus, the combination, with a suspended rod, of a grappling device consisting of claws pivoted to a cross-bar sliding on said rod, toggle-bars having one end pivoted to the extended ends of said claws above said cross-bar and the other end pivoted to said rod, and a flexible connection to said extended claw ends, whereby said claws 40 may be operated, substantially as set forth. 45

In testimony whereof I affix my signature in presence of two witnesses.

JEROME L. BOYER.
